CLIP FOR PIPES, TUBES AND THE LIKE

Alvin J. Kirkpatrick, 5149 N. Kildare Ave., Chicago, Ill.

Filed Mar. 21, 1963, Ser. No. 74,129

Term of patent 14 years

(Cl. D54—1)

Fig. 3.

FIG. 1 is a view in perspective of a clip for pipes, tubes and the like showing the design, in the open position;

FIG. 2 is an end elevational view,

FIG. 3 is a side elevational view,

FIG. 4 is a top plan view, and

FIG. 5 is a view in perspective, all the latter being in the closed position on a pipe shown in dotted lines in this figure.

I claim:

The ornamental design for a clip for pipes, tubes and the like, as shown and described.
